UNITED STATES PATENT OFFICE.

WILLIAM GOFORTH AND ANDREW J. GOFORTH, OF WINDSOR, MISSOURI,
ASSIGNORS OF ONE-THIRD TO BYERS W. HUEY AND GEORGE A. HUEY,
OF SAME PLACE.

WINDOW-FRAME.

SPECIFICATION forming part of Letters Patent No. 245,156, dated August 2, 1881.

Application filed May 5, 1881. (No model.)

To all whom it may concern:

Be it known that we, WILLIAM GOFORTH and A. J. GOFORTH, of Windsor, in the county of Henry, and in the State of Missouri, have invented certain new and useful Improvements in Window-Frames; and we do hereby declare that the following is a full, clear, and exact description thereof, reference being had to the accompanying drawings, and to the letters of reference marked thereon, making a part of this specification.

This invention relates to certain improvements in window-frames; and it consists in the combination and arrangement of parts, as more fully hereinafter set forth, and specifically pointed out in the claims.

In the drawings, Figure 1 shows a vertical sectional view, showing the sash-frame up or in normal position. Fig. 2 represents a horizontal sectional view. Fig. 3 represents a detached sectional view of a portion of the sash-frame; Fig. 4, a modification thereof; and Fig. 5, a vertical sectional view of the window-frame as adapted to car-windows, showing the lower part of the sash-frame down.

The letter A indicates the jambs of the frame, B the sill, and C the soffit. The jambs and soffit are of the ordinary construction; but the sill is inclined downwardly and outwardly, in order to shed rain and dust.

The letter D indicates the sash-frame proper, which is constructed in two sections and confined between the jambs and soffit, setting closely against them. The upper section of the said sash-frame extends from the soffit to the meeting line of the sashes, and is fastened securely to the jamb and soffit in ordinary windows, as indicated in Fig. 1 of the drawings. The lower section of the sash-frame is pivoted at its lower ends to the jamb, and the adjoining ends of the sash-sections are beveled, as indicated by the letter E, in such manner that the lower section of the sash-frame may be swung back or inward, as indicated in Fig. 5 of the drawings. The sash-frame is provided with the usual grooves, F, for the sashes G H. The lower outer portion of the jamb is beveled

at each side, as indicated by the letter I, and the lower edge of the sash-frame, as indicated by the letter K.

The letter L indicates a stop and support for the lower sash, H, the said stop consisting of a transverse upright strip, the upper edge of which is provided with a packing of rubber, M, against which the lower edge of the lower sash rests when the parts are in normal position. The sashes are provided with any suitable devices for holding them in any desired position.

The jamb may be constructed of wood, as indicated in Fig. 3, or of hollow cast metal, as indicated in Fig. 4 of the drawings.

In the modification shown in Fig. 5 the upper section of the sash-frame A and the jamb extend above the inner and outer window-frames, 65 so that the sashes may be concealed when elevated. This modification is designed for car-windows, and the lower sash is a blind-sash, as indicated.

The operation of our invention is as follows: 70 When it is desired to clean the outer faces of the windows or sashes, or to remove said sashes, both of such sashes are let down into the lower section of the sash-frame, which is thrown back, as shown in Fig. 5, when it is evident 75 that the outer faces of the sashes may be readily reached, or the sashes drawn out of the lower section.

We are aware that a sash-frame adapted to swing backward and permit the sashes to be 80 withdrawn is not new, and therefore we do not claim such, broadly.

Having thus described our invention, what we claim, and desire to secure by Letters Patent, is—

1. In combination, jambs A, sill B, and soffit C, the sash-frame D, constructed in two sections, beveled, as shown at E, the lower section being pivoted at its lower ends to the jambs, whereby it may be swung back for the 90 purpose of cleaning the outsides of the sashes and window-panes, substantially as specified.

2. In combination with the lower sash-frame section and the inner sash, the sash stop and

support, arranged substantially as and for the purposes specified.

3. In combination with the inclined sill and stop, the jamb and pivoted lower sash-section, ~~s~~ beveled, as indicated by the letters I K, substantially as and for the purposes specified.

In testimony whereof we affix our signatures,

in presence of two witnesses, this 12th day of April, 1881.

WM. GOFORTH.
ANDREW J. GOFORTH.
